(57) **CLAIM**

The ornamental design for a scanner, as shown and described.

DESCRIPTION

FIG. 1 is a perspective view of a scanner;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof; and,

FIG. 8 is another perspective view of the scanner showing

trays in an opened configuration.

Broken lines and unshaded portions contained within broken lines depict portions of the scanner that form no part of the claimed design.

The dot-dash lines depict a boundary between claimed and unclaimed subject matter, and form no part of the claimed design.

The unshaded surface area contained within the dot-dash boundary lines of the front-top panel forms no part of the claimed design.
